UNITED STATES PATENT OFFICE.

LOYD G. KIMBER, OF SACRAMENTO, CALIFORNIA, ASSIGNOR TO CALIFORNIA ALMOND GROWERS EXCHANGE, OF SAN FRANCISCO, CALIFORNIA, A CORPORATION OF CALIFORNIA.

APPARATUS FOR SEPARATING THE MEAT FROM SHELLS OF CRACKED NUTS.

Application filed December 13, 1922. Serial No. 606,725.

To all whom it may concern:

Be it known that I, LOYD G. KIMBER, a citizen of the United States, residing at Sacramento, in the county of Sacramento and State of California, have invented certain new and useful Improvements in Apparatus for Separating the Meat from Shells of Cracked Nuts, of which the following is a specification.

10 This invention relates to a separating apparatus designed particularly for separating the meats from the shells of cracked nuts.

The principal objects of this invention are to provide an apparatus which is adapted for operation at an extremely low cost; one wherein the material to be separated is delivered in successive charges to the action of the separating medium, thereby enabling the separation of material of one charge before another charge is presented. A further object is to provide a novel form of material feed mechanism and to provide a means for discharging the meats from the apparatus.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more clearly comprehend the invention, reference is directed to the accompanying drawings, wherein—

Fig. 1 is a view in side elevation of the preferred embodiment of my apparatus.

Fig. 2 is a detailed sectional view of the reciprocating gate and the means for operating the same to deliver intermittent charges of material to successive elevating pockets.

Fig. 3 is a view in end elevation of the apparatus illustrated in Fig. 1.

Fig. 4 is a vertical sectional view of the separating duct taken on line 4—4 of Fig. 3.

Fig. 5 is also a view of the separating duct taken on line 5—5 of Fig. 4.

Referring more particularly to the drawings, wherein like characters designate corresponding parts, 1 indicates a suitable elongated frame supported by legs or members 2. The frame at one end carries the material receiving hopper 3 having an inclined bottom 4 falling short of connecting with the front wall 5, thus providing an open space 6, the closing wall of which comprises the flight of an endless conveying belt 7. The front wall 5 of the hopper is provided with an outlet 8 normally closed by a vertically reciprocating gate 9 which is adapted to rest on a flight of the conveying belt. The conveying belt is of the endless type and is horizontally disposed and operates around supporting rollers or drums 10 to dispose the upper flight thereof in substantially horizontal position in contact with the lower edge of the bottom 4 and lower edge of gate 9. Forwardly from the gate 9 extends an arm 11 carrying a roller 12 adapted to rest on the upper flight of the belt and limits the downward movement of the gate. A shaft 13 mounts one of the rollers 10 and is connected with a drive mechanism for operating the roller to drive the belt. The arm 11 is provided with a lateral extension 13' mounting the idler 14, which is adapted to contact with the surface of a gate opening cam 15 secured to the shaft 13.

On each revolution of the shaft 13 it will be observed that the action of the cam 15 on the idler 14 will raise the gate 9, permitting the belt 7 to deliver a charge of material from the hopper, which charge is cut off immediately on the peak of cam 15 passing beneath the idler 14, permitting the gate 9 to drop.

Vertically disposed above the frame, adjacent the discharge of the belt 7, is an elevator housing 16, and within the same is positioned a pocketed endless elevator 17 operating around the top and bottom drums 18, the upper of which is preferably driven by a belt connection 19, and said drum also transmits power through a belt 20 to a wheel

21 on the end of shaft 13', thus operating the conveyer 7 in timed relation with the operation of the elevator 17.

5 A chute 21 extends outwardly and upwardly from the wall of the housing 17 to a point to receive the material transferred by the conveyer belt 7 from the hopper, and said chute is adapted to deliver successive charges into successive buckets of the elevator as the same approach the inlet opening 22 in the wall of the housing 16.

10 To maintain the surface of the belt 7 clean, I position a suitable pivotally mounted brush 23 beneath the chute 21 with the brush bristles in contact with the surface of the belt.

15 Projecting inwardly into the elevator housing 16 at a point below the upper elevator supporting drum 18 to receive the material discharged by the passage of the successive buckets over the upper drum, is a downwardly inclined plate 24 forming a directing wall for conveying the unseparated material exterior of the elevator housing 16 through an opening 25 in the housing wall.

20 A separating flue or air blast duct 26 extends vertically above the frame 1 at one side of the elevator housing 16, and into the same discharges the unseparated material passing through the opening 25. At a point below said opening 25 the duct 26 is shut off by a transverse baffle or chute 27 extending laterally therefrom. The air blast forced upwardly in said duct 26 is divided beneath the baffle 27 and passes upwardly through the divided channels 28 which communicate with the duct at a point above the baffle 27 through openings 29 in opposite sides of the duct wall at a point below the opening 25.

25 It will be observed that the air blast issuing from the openings 29 is directed transversely of the duct and causes a separating action on the material as it enters the duct through the opening 25 to elevate the chaff and shells upwardly in said duct 26, permitting the heavier particles, such as the meats, to drop onto the baffle 27 by which they are conveyed from the duct on to the endless conveying belt 30 disposed at one side of the frame 1 and which receives the meats and discharges the same through a chute 31 at the end of the frame 1.

30 The upper end of the duct 26 terminates in a chamber 32 at one side thereof into which the chaff and shells separated from the nut meats are conveyed by the air blast.

35 The chamber is vented by a screen 33 and is provided with a door 34 for permitting access thereto. The separated chaff and shells discharge from the chamber through the opening 34', through which extends a chute 35.

40 A blower 36 provided with an inlet controlled by a gate 37 is connected at its outlet end 38 with the lower end of the duct 26

and supplies air under pressure in the direction of the arrows—Fig. 4, thereto.

45 A motor 39 is carried by the frame and is connected through a drive belt 40 with the blower 36. The belt 19 which drives the elevator passes at its lower end over a pulley 40, which pulley is in turn driven through a reduction drive 41 by the motor 39.

50 It will be apparent that I have provided a mechanism whereby intermittent charges of material released from the hopper are delivered into successive buckets of an elevator on the registering of the buckets with the charge receiving chute, and also that I have provided an air blast separator wherein the air current is divided prior to acting on the material to be separated and acts on the material from opposite directions.

55 Having thus described my invention, what I claim as new and desire to secure by Letters Patent is:—

1. An apparatus for separating the shells from the meat of cracked nuts, comprising a hopper having an outlet, a continuously moving pocketed elevator for elevating the material to be separated, means between the elevator and hopper for receiving successive charges of material from said hopper outlet and for delivering the same to the pockets of said elevator as the pockets are moved into co-operative relation with the said means, a gate for said hopper outlet, means for intermittently operating said gate whereby material is fed from said hopper outlet in intermittent charges onto said conveyor, a duct downwardly into which said elevator discharges the material to be separated, and means therein for separating the meat from the shells.

105 2. An apparatus for separating the shells from the meat of cracked nuts, comprising a hopper having an outlet, a continuously moving pocketed elevator for elevating the material to be separated, means between the elevator and hopper for receiving successive charges of material from said hopper outlet and for delivering the same to the pockets of said elevator as said pockets are moved into co-operative relation therewith, a gate for said hopper outlet, means operated in timed relation with the movement of the elevator for intermittently actuating said gate to admit successive charges of material to flow from said hopper outlet onto the conveyor, a duct downwardly into which said elevator discharges the material to be separated, and means therein for separating the meat from the shells.

110 3. An apparatus for separating the shells from the meat of cracked nuts, including a continuously moving conveyor means, an air duct provided with divided channels leading from the duct at one point and intersecting the same at another point through opposite sides of the duct, means for directing ma- 115

material discharged from said conveyor members downwardly into said duct at a point above the connection of said channels therewith, by which lighter material is acted upon by the opposing air blasts and forced upwardly in said air duct, a trap into which the upper end of said duct leads and into

which said lighter material is discharged, an outlet in said duct through which the heavier material drops by gravity, and a blower for creating an air blast upwardly in said duct. ¹⁰

In testimony whereof I have signed my name to this specification.

LOYD G. KIMBER.
